UNITED STATES PATENT OFFICE.

CARL ROTHACKER, JR., OF PFORZHEIM, GERMANY.

OPERA-GLASS.

SPECIFICATION forming part of Letters Patent No. 309,407, dated December 16, 1884.

Application filed August 4, 1884. (No model.)

To all whom it may concern:

Be it known that I, CARL ROTHACKER, Jr., a citizen of Germany, and residing at Pforzheim, Germany, have invented new and useful Improvements in Opera-Glasses, of which the following is a specification.

This invention relates to a binocular opera-glass adapted to be folded into the form of and be carried as a watch-chain trinket; and the invention consists in the folding or collapsible construction of frame, hereinafter described instead of the usual telescopic double-barreled body.

Reference is to be had to the accompanying drawings, forming part of this specification, in which similar letters of reference indicate corresponding parts in all the figures.

Figure 1 is a face view of my improved opera-glass, the same being folded. Fig. 2 is a side view of the same folded. Fig. 3 is a side view of the same opened. Fig. 4 is a side view of the same partly folded.

The object-glass mounts A are short cylinders carried by pairs of arms f, working on a common hinge, so as to be capable of being folded together, with the eye-pieces B inclosed between them. The said arms are hinged to a cross-head, a, fitted to slide b upon the parallel limbs e of a central U-shaped frame, the eye-pieces B being also carried by a pair of arms, h, hinged to another cross-head, d, fitted to a slide, c, on the same U-shaped frame, the two pairs of lenses being retained in their extended position, respectively, by a connecting-link, l, holding the arms f f, and by a bolt, q, working in the guides p and g of the arms h h, and thus locking the hinged pairs of arms rigidly together, as shown in Fig. 3.

When the opera-glass is to be closed or folded, the cross-bar d, on which are the arms h,

carrying the eye-pieces B, is moved up toward the cross-bar a, the eye-pieces B being folded against each other and brought together within and at opposite sides of the bow end of the U-shaped frame, after which the two object-glass mounts A are folded back and brought together at opposite sides of the eye-pieces B, so as to inclose the latter and the U-frame between them. 45

To protect the object-glasses, their mounts A are provided with hinged covers D, which inclose their outer ends, (when closed,) one cover having a hinged clasp or link, O, which engages with a catch, r, on the other and securely locks the whole in the closed position. (See Fig. 1.) 50

The glass is readily extended for use, and is focused by sliding the cross-heads on the central U-frame. (See Fig. 3.)

The cross-head a, which carries the object-glasses, is furnished with a swivel, K, for attachment to a chain. 60

Having thus described my invention and the manner of employing the same, I claim—

The herein-described construction of folding binocular opera-glass in which the lens-mounts are hinged to cross-heads sliding on a U-shaped frame, and are adapted to be extended for use or to be folded into the form of a trinket, and to be retained in either of those positions, substantially in the manner and by the means herein specified. 65 70 75

In testimony whereof I have signed my name to this specification in the presence of two subscribing witnesses.

CARL ROTHACKER, JR.
